(57) **CLAIM**

The ornamental design for a main unit of electronic cigarette as shown and described.

DESCRIPTION

1. Main unit of electronic cigarette

1.1 : Front

1.2 : Back

1.3 : Left

1.4 : Right

1.5 : Top

1.6 : Bottom

1.7 : Perspective

1.8 : Perspective

1.1 is a front view of a main unit of electronic cigarette showing our new design; 1.2 is a rear view thereof; 1.3 is a left view thereof; 1.4 is a right view thereof; 1.5 is a top view thereof; 1.6 is a bottom view thereof; 1.7 is a front, top and right side perspective view thereof; and 1.8 is a front, bottom, and left side perspective view thereof; The color deviations among the reproductions are due to shadow or light reflections.

1 Claim, 8 Drawing Sheets
